Patented June 1, 1920.

Inventor:
George T. Dochtermann
by Wilbur M. Stone

his Attorney.

UNITED STATES PATENT OFFICE.

GEORGE T. DOCHTERMANN, OF PASSAIC, NEW JERSEY.

SPARK-PLUG.

1,342,205.

Specification of Letters Patent.

Patented June 1, 1920.

Application filed January 29, 1919. Serial No. 273,756.

To all whom it may concern:

Be it known that I, GEORGE T. DOCHTERMANN, a citizen of the United States, and a resident of Passaic, in the county of Passaic and State of New Jersey, have invented certain new and useful Improvements in Spark-Plugs, of which the following is a specification.

This invention relates to spark plugs for hydrocarbon engines. The object of my improvements is to provide a device of the class specified in which those portions of the plug which are normally exposed to carbon and oil deposit are protected against access of carbon and oil. A further object is to provide improved priming means in connection with the other improvements.

Other features will appear later herein. My improvements comprise features illustrated in their preferred embodiment in the drawing accompanying this specification wherein the figure is a vertical section of a spark plug embodying my improvements.

The usual tubular body 2, of some approved design is provided with the usual threaded end 3 for mounting the plug in place for use. The bore 4 of body 2 is enlarged at its upper end 5 to provide seat 6 for shoulder 7 of tubular insulating member 8. Said insulating member 8 may be held in place in body 2 by means of the usual hollow nut 9. Within lengthwise passage 10 of insulator 8 is supported tubular conductor 11. The upper end of said conductor is provided with an outer threaded portion 12 onto which is screwed nut 13 for holding said conductor in place with its shoulder 14 against the lower end of insulating member 8. Between nuts 13 and 22, the connecting wire may be secured. On the top of said conductor 11 is screwed priming cup 15. Said cup is provided with dished upper wall 16 from which one or more passages 17 lead to annular channel 18, the upper wall 19 of which forms a valve seat or closing member for the upper end of conductor tube 11, when screwed down thereagainst. On the lower end of tube 11 is secured flange 20, which projects outwardly

all around, beyond the bore 4 of body 2 and 50 in close proximity to the lower end 21 thereof, thus forming a spark gap and at the same time providing an efficient obstruction to the entrance of carbon charged gas and oil to the space within the lower part of 55 body 2. By this means long life and efficient service is assured the plug. Furthermore the peculiar form of my improved priming cup provides a tight seal for the top of tube 11 and said cup may be readily 60 removed for cleaning both it and the channel in said tube. Also the absence of springs, balls, and other loose pieces commonly used in priming cup caps eliminates the possibility of their loss when taking the cup off 65 for cleaning.

I claim:

1. In a device of the class described, a tube, and a priming cup adjustably mounted on one end portion thereof, said cup having 70 a rigid member arranged to close the adjacent end of said tube when said cup is adjusted in one direction and having a passage in communication with the interior of said tube when said cup is adjusted in another 75 direction.

2. In combination with a tube, a priming cup threaded on one end portion of said tube and having a rigid member arranged to close the adjacent end of said tube when 80 the cup is threaded onto the tube, said cup being provided with a passage in communication with the interior of said tube when said cup is threaded partially off of said tube. 85

3. A device of the class described including a tube, a priming cup threaded on one end portion of said tube and having a dished upper face, a member rigid with said priming cup arranged to close the adjacent end 90 of said tube when said cup is secured down against said end, said cup having an annular channel therein below said tube closing member and having a passage from said dished face to said annular channel. 95

In witness whereof, I hereby affix my signature this 28 day of January, 1919.

GEORGE T. DOCHTERMANN.
